UNITED STATES PATENT OFFICE.

MOSE MOSES, OF JACKSON, TENNESSEE, ASSIGNOR OF ONE-HALF TO JOHN C. POOL, OF JACKSON, TENNESSEE.

DRAW-BAR PRESS.

1,184,559.

Specification of Letters Patent. Patented May 23, 1916.

Application filed June 16, 1915. Serial No. 34,479.

To all whom it may concern:

Be it known that I, MOSE MOSES, a citizen of the United States, residing at Jackson, in the county of Madison and State of Tennessee, have invented certain new and useful Improvements in Draw-Bar Presses; and I do hereby declare the following to be a full, clear, and exact description of the invention, such as will enable others skilled in the art to which it appertains to make and use the same.

This invention is an improved press for use in shortening the draw bars of locomotives, which become unduly lengthened as a result of the stress to which they are subjected in pulling the trains, the object of the invention being to provide an improved press of this character by means of which a locomotive draw bar may be readily shortened and which requires the services of from two to four men in its operation while the operation of shortening a draw bar, as heretofore practised, requires the services of from six to eight men.

The invention consists in the construction, combination and arrangement of devices hereinafter described and claimed.

In the accompanying drawings:—Figure 1 is a side elevation of a draw bar press constructed in accordance with my invention. Fig. 2 is a plan of the same. Fig. 3 is a vertical longitudinal sectional view of the same. Fig. 4 is a detail elevation of the lifting hook. Fig. 5 is a detail side elevation showing the press coupled to a hydraulic power press for operation thereby. Fig. 6 is a similar view showing the press connected to an electric power press.

In the embodiment of my invention, I provide a box 1 which comprises a bottom 2 and a pair of spaced side walls 3 which rise from the bottom. A head 4 is arranged between the walls and at one end of the box. The walls are provided at the opposite end, 45 at their upper sides, with lugs 5.

A matrix base 6 is arranged in the bottom of the press box and terminates at one end in the head 4. The upper side 7 of the matrix base is shaped to correspond with the shape of one side of a drawbar and to adapt the press for use in connection with drawbars of different forms, the matrix base is also provided in its upper side with a removable member 8. This member is ar-

ranged in a recess 9 and bears at one end 51 also against the head 4.

When the member 8 is removed the matrix base conforms to the shape of one form of drawbar and when the member 8 is in place in the recess 9 the matrix base, 60 together with the said member 8, conforms to another form of drawbar, as will be understood. A recess 10 is in the upper side of the matrix base at the end opposite the head and the matrix base also has a transverse 61 cross sectionally triangular recess 11 in which a lifting cam 12 is pivotally mounted as at 13. Said cam is normally arranged in the recess with one side of the cam flush with the upper side of the matrix base as 70 indicated in full lines in Fig. 3. The cam may be turned to a vertical position and caused to project above the matrix base in order to lift a drawbar from the box after the drawbar has been shortened, as indicated in dotted lines in said figure.

A lever head 14 is pivotally mounted between the lugs 5 as at 15 and is connected by links 16 to a plunger 17 which is longitudinally movable in the guide recess 10 of 8 the matrix base. A lever bar 18 may be detachably secured to the lever head by placing said bar in a socket 19 with which the lever head is provided. The pivot shaft 13 of the lifting cam is provided at its ends 8 with heads 20 having radial sockets 21 for the reception of bars 22, one of which is indicated in dotted lines in Fig. 1 and by means of which the cam may be readily turned to lift and facilitate the removal of 9 a drawbar after the drawbar has been shortened.

In the operation of my improved press a drawbar is first heated and placed in the press, on the matrix base and with 9 one end against the head 4, the plunger 17 having been drawn outwardly a sufficient distance, by upturning the lever head 14. When the draw bar has been thus arranged the lever head 14 is turned downwardly by 1 its bar 18, thus forcing the plunger inwardly and hence shortening the draw bar between the plunger and the head 4, the inner limit of movement of the plunger being determined by the shoulder 23 the space 1 between said shoulder and the head 4 corresponding with the required standard length of the drawbar. The removable

- member 8 is provided with a recess 24 in which is an eye 25 for engagement by a hook 26, wherewith to lift said member 8 when it is desired to remove the same.
- 5 To hold the drawbar and prevent it from buckling while being shortened in the press suitable rods 27 are provided which may be placed in and extended through openings 28 in the wall 3.
- 10 When it is desired to use my improved press in connection with hydraulic electric power for operation thereby instead of manually, I remove the lever 14 and the links 16 and connect a coupling head 29 to the 15 plunger 17 by means of a pin 30, said coupling head having a shank 31 for attachment to a hydraulic cylinder or electric power apparatus as shown in Figs. 5 and 6 respectively so that the press may be operated by either hydraulic or electric power.

Having thus described my invention, I claim:—

1. A drawbar press of the class described comprising a box, having a head at one end, 25 and a lever head pivotally mounted at the other end, a matrix base in the bottom of the box, terminating at the head and provided in its upper side with a guide recess at the end opposite the head, a plunger arranged for movement in said recess and 30 connections between the plunger and the lever head to enable the plunger to be operated by the lever head.

2. In a drawbar press a press box, a head 35 therein, a matrix base, a plunger, means to operate the plunger and a lifting cam arranged in a recess in the upper side of the matrix base said lifting cam having a shaft pivotally mounted in the walls of the press 40 box and provided at its ends with means whereby said cam may be turned.

3. In a drawbar press a press box, a head therein, a matrix base, a plunger, means to

operate the plunger, said matrix base having a detachable member in its upper side 45 corresponding with one form of drawbar, the recess corresponding with another form of drawbar.

4. A drawbar press of the class described having a matrix base, a head in one end of 50 the base, a shoulder at the other end of the base, a plunger, and means by which the plunger may be operated, said shoulder limiting the inward movement of the plunger.

5. A drawbar press of the class described 55 having a matrix base, a head in one end of the base, a plunger at the other end of the base, operating means for the plunger, and means to prevent the drawbar from buckling while being subjected to pressure by the 60 plunger.

6. A drawbar press of the class described having a matrix base, sides rising vertically from the base, a head located between the sides at one end of the base, the opposite end of the base having a recess, a shoulder at the end of the recess, a plunger slidably mounted in said recess, a lever head pivotally mounted to and between the sides at said other end of the base, and a link connected to the lever head and plunger, said shoulder limiting the inward movement of 70 the plunger.

7. A drawbar press of the class described having a matrix base, stationary sides rising vertically from the base, a head located between the sides at one end of the base, a plunger slidably mounted between the sides at the other end of the base, and means by 75 which the plunger may be operated.

In testimony whereof I affix my signature in presence of two witnesses.

MOSE MOSES.
